UNITED STATES PATENT OFFICE.

LEWIS STEELMAN, OF MILLVILLE, NEW JERSEY.

TWYER STRUCTURE FOR GAS-PRODUCERS.

1,172,070.

Specification of Letters Patent. Patented Feb. 15, 1916.

Application filed September 26, 1914. Serial No. 863,610.

To all whom it may concern:

Be it known that I, LEWIS STEELMAN, a citizen of the United States, residing at Millville, in the county of Cumberland, 5 State of New Jersey, have invented certain new and useful Improvements in Twyer Structures for Gas-Producers, of which the following is a specification.

My invention has relation to twyer structures for gas producers, and is designed to provide a twyer turret of novel and efficient character by which a good distribution of the air is effected and which is also provided with a novel arrangement of scraping devices.

In the accompanying drawing, in which I have shown the preferred embodiment of my invention: Figure 1 is a central vertical sectional elevation through the lower or base portion of the combustion chamber of the gas producer and showing a turret embodying my invention; and Fig. 2 is a sectional plan view of the twyer turret.

Referring to the drawings: 1 designates the combustion chamber of a typical gas producer or generator. This chamber is formed in any preferred manner with walls 2 of brick incased in sheet iron, and at its lower portion is constructed to form an internally flaring discharging face 3, which terminates in an ash discharging throat 7, opening into a basal ash table chamber 35. The producer as an entirety is conveniently rested upon pedestals 4 springing from any appropriate foundation.

5 is a circular basin through which the pedestals pass and into the upper portion of which the lower part of the furnace walls extend. This basin is filled with water 6 to form the water seal of the producer and receive the ash. Centrally within the basin and being conveniently a part of it, is a foundation 8 upon which is superimposed the lower member 9 of a ball race, the upper member of which is designated 15, and between which members are disposed the balls 16. The upper member 15 of the ball race is connected with the under surface of an ash table 10 upon which is superimposed and to which table is rigidly connected the rotatable twyer turret 11.

The twyer turret is of hollow construction, preferably a casting and preferably of what I may term stepped pyramidal form.

12 are the twyers, in the form of turret shown radiating outwardly from the hollow

interior of the turret, and disposed in three comparatively equidistant horizontal planes, which may be considered as the steps 11^x of the turret. The exterior or crown surfaces of these steps are formed with or overlapped by curved scrapers 13, which, as will be understood, series by series radiate outward in corresponding curves. With the exception of the scrapers upon the cap 12^x 65 of the turret, each series of scrapers is correspondent in number to the twyers which discharge over the step upon which said series is located, so that, as the steps of the turret go down, so to speak, there are increasing numbers of series both of twyers and twyer scrapers upon the respective steps.

It is, in this connection, to be understood that I do not limit myself to the number of steps, or to the number of twyers, or to 75 the precise or relative correspondence between them, although in practice I find it convenient to employ a three-step turret embodying the twyers shown. I do not, moreover, limit myself to the number or special 80 construction of twyer scrapers employed, nor to the degree or general trend of their curvature when curved, but prefer that they should numerically correspond with the twyers of the steps upon which they are placed 85 and be curved in the direction of the curvature of the twyers, substantially as represented in Fig. 2. Obviously, however, the twyers themselves need not be curved, but when curved as is preferable, their curvature should be backward so that in the rotation of the turret in the direction of the arrow upon Fig. 2 the blasts through them should be backward.

The twyer turret as explained, is connected with the ash table so as to rotate with it, and the diameter of its lowest step or basal portion is less than the diameter of the ash table, so that the ash which gravitates through the discharging throat 7 of 100 the combustion chamber may drop upon the peripheral outer face of the table and be thereon encountered by and subjected to the action of a series of inwardly radiating scraping rods 27, which are introduced 105 through tubular boxings 28, in the lower walls of the furnace.

The rotary movement of the turret and ash table may be accomplished by any preferred means. I find it convenient, however, to form the underface of the table as a beveled toothed face 14, with which is en-

gaged a pinion 17 on the inner end of a pinion shaft 18 rotatable in suitable bearings 19 by a driven spur wheel 20 connected through an idler wheel 21 with the driving spur wheel 22 upon a shaft 23 housed in bearings 24 and conveniently provided with driving pulleys 25 and also with a crank handle 26. Obviously through this gearing a continuous rotary movement may be imparted to the ash table and the twyer turret.

29 is a conduit extending horizontally beneath the basin and turning vertically upward so as to open and discharge into the hollow interior of the twyer turret. Into 15 the outer extremity of this conduit extend a steam injector 30 and an air injector 31, the conduit itself opening to the atmosphere.

32 is a damper fitting over the injectors 20 and adapted to be vertically lifted and dropped within a bearing 33, upon the exterior of the basin, to control the admission of the outside air to the conduit. The action of the injectors in conjunction with the 25 admission of air to the conduit, occasions a forced draft to the twyer turret controllable by the damper.

34 are openings in the ash table chamber

35, through which access to said chamber may be had.

Having thus described my invention, what I claim as new and desire to secure by Letters Patent, is:—

1. A rotary twyer-turret, comprising a hollow stepped pyramidal structure, each step consisting of a circular horizontal series of radiating twyers, whose exterior or crown surfaces are formed with curved outwardly radiating scrapers; substantially as described.

2. A rotary twyer-turret, comprising a hollow stepped pyramidal structure, each step consisting of a circular horizontal series of radiating twyers, whose exterior or crown surfaces are formed with curved outwardly radiating scrapers, both the twyers and the scrapers having a backward curvature with respect to the direction of rotation of the structure; substantially as described.

In witness whereof I have hereunto signed my name this 16th day of September, 1914.

LEWIS STEELMAN.

In the presence of—

J. BONSALL TAYLOR,
C. D. McVAY.
